UNITED STATES PATENT OFFICE.

NEWTON E. CHARLTON, OF CLAYTON, NEW MEXICO.

SAFETY-RAZOR-BLADE HOLDER.

Application filed April 13, 1925. Serial No. 22,808.

To all whom it may concern:

Be it known that I, NEWTON E. CHARLTON, a citizen of the United States, residing at Clayton, in the county of Union and State of New Mexico, have invented certain new and useful Improvements in Safety-Razor-Blade Holders; and I do declare the following to be a full, clear, and exact description of the invention, such as will enable others skilled in the art to which it appertains to make and use the same.

My invention relates to improvements in holders for safety razor blades and has reference more particularly to holders which are designed for use while stropping the blades, the object being to provide an exceptionally simple and inexpensive device of this character, yet one which will be highly efficient and in every way desirable.

With the foregoing in view, the invention resides in the novel subject matter herein-after described and claimed, the description being supplemented by the accompanying drawing.

Figure 1 is a side elevation.
Figure 2 is a back edge view.

Figure 3 is a fragmentary side elevation with the blade-holding slide removed.

Figure 4 is an inner side elevation of the blade-holding slide.

Figure 5 is a transverse sectional view on line 5—5 of Fig. 1.

In the drawing above briefly described, the numeral 1 designates a suitably shaped elongated handle having an elongated, longitudinally disposed head 2 at one end. This head is transversely tapered from its back edge 3 to its front edge 4 to lie in the requisite manner upon an ordinary razor strop. The head 2 is formed with a longitudinal recess 5 which opens through one of its flat sides and also opens through the back edge 3 and the front edge 4, said recess having a flat bottom and being provided with forwardly converging, undercut end walls 6. This recess is adapted to receive a safety razor blade 7, and its bottom is provided with any desired means for holding the blade in such position that one of its edges projects forwardly from the front edge 4 of the head 2. The present disclosure is designed for holding one well known form of safety razor blade, and the bottom of the recess 5 is formed with a pair of upstanding studs 8 for reception in openings in said blade.

A flat-sided slide 9 is snugly receivable in the recess 5 to clamp the blade 7 therein, said slide being transversely tapered from its back edge to its front edge and having forwardly converging beveled ends 10 for sliding engagement with the undercut, forwardly converging end walls 6 of the recess, so that when the slide is forced into the recess from the back edge of the head 2, it will wedge tightly in place and will effectively clamp the blade 7. If the studs 8 are of a length to project slightly beyond the blade 7, the inner face of the slide 9 will be provided with a pair of shallow grooves 11, opening through the front edge of said slide, to receive the projecting ends of the studs, as shown.

It will be seen from the foregoing that the device is exceptionally simple and inexpensive, yet that it will firmly hold a safety razor blade in such position as to permit it to be readily stropped upon an ordinary razor strop, or to permit honing of the blade whenever necessary. On account of the advantages existing for the details shown, they are preferably followed, but within the scope of the invention as claimed, slight variations may be made and as above stated, the device may be so constructed as to hold any well known form of razor blade.

I claim:

A safety razor blade holder comprising a one piece handle having an integral longitudinal straight-edged head at one end, said head being transversely tapered from its back edge to its front edge and having an elongated recess which opens through said back and front edges and through one flat side of the head, said recess having straight under-cut end walls which converge toward said front edge, the bottom of said recess being provided with means to engage a safety razor blade and hold the latter against shifting on said bottom, and an elongated slide plate free of connection with the head and handle and adapted to be forced into said recess from its back edge toward its front edge, said slide plate being transversely tapered from its back to its front edge and having beveled forwardly converging straight ends for tight wedging contact with the ends of said recess.

In testimony whereof I have hereunto affixed my signature.

NEWTON E. CHARLTON.
